WILLIAM H. MASON, OF EASTON, PENNSYLVANIA.

PROCESS OF PREPARING HOLES FOR BLASTING.

1,165,691.

Specification of Letters Patent. Patented Dec. 28, 1915.

Application filed January 20, 1915. Serial No. 3,295.

To all whom it may concern:

Be it known that I, WILLIAM H. MASON, a citizen of the United States, and a resident of Easton, county of Northampton, and 5 State of Pennsylvania, have invented certain new and useful Improvements in Processes of Preparing Holes for Blasting, of which the following is a specification.

My invention relates to a process for the 10 preparation of holes for blasting and is particularly applicable in carbonate rock, such as the various types of limestone, etc., and also gypsum rocks, which rocks are affected by the application of heat so that they may 15 be softened and removed by water after being burned.

It becomes possible by the present invention to prepare holes for the reception of 20 large quantities of explosives with a comparatively small expense for drilling, and to concentrate the explosive where it will be most effective.

According to the practice now generally in 25 vogue, in order to make use of the necessary quantities of explosives, and thereby obtain satisfactory results, it is customary to drill either a large number of small holes with close spacing or a proportionately smaller number of larger holes; the object being in 30 each case to get the required amount of explosive as low down in the stone as is practicable, but with holes of this type it is necessary to distribute the explosive over a considerable length of the hole and less efficient 35 results are obtained than if the explosive were more concentrated in the lower portion of the hole. The expense of drilling such a large number of holes or a proportionate number of smaller holes is considerable, and 40 the cost of carrying on extensive blasting operations in such manner becomes quite burdensome in a large quarry.

Resort has been sometimes had to the 45 practice of "squeibbing" or "springing" holes for blasting, that is to say, introducing and exploding therein a small quantity of explosive for the purpose of enlarging the hole at such point in order to permit of the reception in such enlarged cavity of an increased 50 amount of explosive, but such practices are recognized as being extremely dangerous,

the material where the enlargement is sought to be made is not left in such condition that it may be removed, crevices are likely to be opened up in the squibbing operation, and it 55 is impossible to tell how large a space has thus been formed until after it has been filled with powder, dynamite, etc., when it is too late to make any change, and for these and other reasons it is recognized that the 60 practice of squibbing holes for blasting is dangerous, unsatisfactory and unreliable. Furthermore, the expense of carrying on blasting operations in this way is very considerable. 65

According to the present invention a hole is formed, as by drilling in the ordinary way, and after the hole is drilled heat is applied therein in the neighborhood where an enlargement is desired to be made, and in 70 the case of limestone and similar rocks this results in the burning of the rock to lime, which can be readily hydrated and washed out, as by applying a stream of water for this purpose. 75

The application of heat may be accomplished in a variety of ways, but it is preferably applied by the introduction and combustion of solid fuel in the neighborhood where the heat is desired to be applied, provision being made for supplying air to support combustion, and after the burning has been completed the decarbonated and chemically changed material may be hydrated and flushed out as above described. 80

To supply the air for combustion I preferably introduce a pipe into the hole, the pipe having a diameter considerably less than the diameter of the hole so as to leave an opening for the introduction of fuel. Such pipe 90 is of a length so that its lower end is in the neighborhood where the hole is desired to be enlarged and air is supplied thereto, a controlling valve being preferably provided for governing the amount of air to be admitted. 95

The fuel for combustion may be supplied in different ways but preferably solid fuel is introduced in the the drill hole alongside the air pipe. The fire may be started by introducing a piece or pieces of oil-soaked wood which may be ignited and lowered to the 100

neighborhood where the enlargement is desired to be made, preferably at the bottom of the hole, or ignited after being lowered into place, as by means of a torch, air being furnished through the air pipe to support this combustion and the fuel for continuing the combustion may be supplied through the hole as, for example, by the introduction of coke or coal in sizes sufficiently small to pass down through the drill hole, and as the combustion progresses from below the fuel is fed, somewhat as in the case of a magazine stove, being supplied from above as fast as it is used up and as there is room for the reception of additional fuel at the neighborhood of combustion. As the combustion progresses, the ashes, of course, fall to the bottom and accumulate. When the ashes have filled the hole up as far as the enlargement is desired the feeding of the fuel is discontinued, and when such fuel as remains is consumed the fire goes out and the air may be shut off.

The rate of combustion can, of course, be controlled by the air valve governing the amount of air admitted, since it is readily possible, if too much air is admitted, for the combustion to become too rapid and to burn away the pipe and overburn the stone; if limestone, making the lime difficult to slake. I preferably provide means whereby the progress of combustion can be observed from outside, and to this end I may provide a peep-hole with a transparent covering whereby the workman can look down the air pipe and can judge by the appearance of the heated interior thereof the rate of combustion, and if the pipe appears to be too hot he can shut off a portion of the air, or if the redness of the heated pipe is not sufficiently pronounced he can introduce additional air by means of the air valve, as will be understood. The extent to which the rock is decarbonated or otherwise changed in chemical make up about the drill hole, which, of course, determines the enlarged opening provided in this manner, can be readily controlled by the operator as by varying the amount of fuel consumed, the rate of combustion and the length of time during which it is maintained, all of which, of course are under the complete control of the operator, who can take care of burning operations in a number of holes at the same time. With air supplied by pressure in the manner described the combustion is from the bottom. It will be understood that this situation may be reversed and the fuel burned from the top by drawing the air down the hole, as by connecting the air pipe to an exhauster, which creates a suction downward.

After the operation of burning has been carried on to an extent sufficient for the requirements, and all the fuel consumed that is desired to be used, the air is shut off.

Suitable connection can be made for the introduction of water, as by the pipe used for supplying air for combustion, or by another pipe, and water is supplied thereby and permitted to escape from the upper end of the drill hole, carrying with it the ashes and the hydrated and dissolved material of the decarbonated rock, and finally the cleaning out may be completed as by means of pumps, such as ordinarily are used for cleaning out the sludge from the bottom of the drilled holes, and as are available in all quarries, the hole when finally cleaned of the soluble or pasty hydrated decarbonated material being greatly enlarged at the point of burning and adapted to receive a quantity of explosive in compact concentrated form.

The burning of rock, as limestone or gypsum, takes place more readily in the presence of moisture or steam, and ordinarily the moisture normally contained in the rock which is transformed into steam during the combustion is sufficient for supplying all needed moisture. For the most effective burning operation, however, in rocks where the moisture contained is abnormally low, a steam or water pipe can be introduced alongside the air pipe, and such quantities of moisture as may be needed to most effectively perform the disintegration of the rock may be provided, this being under the control of the operator as by means of a suitable valve or valves. If desired, steam or water may be introduced through the air pipe.

With the foregoing and related objects in view, my invention consists in the processes, operations and steps herein set forth and claimed.

In the accompanying drawing forming a part of this specification, I have shown in the single figure thereof, for the purpose of making my invention clearly understood, a cross-sectional view of rock having a drilled hole and apparatus therein in accordance with the present invention. In the said drawing, the rock in which the hole is made, and which is of a material such as limestone, gypsum or the like, and which can be calcined, is indicated by the reference numeral 1, and the drilled hole, which is preferably of such small diameter as can be most effectively used and economically formed, is indicated by the reference numeral 2.

3 indicates the air pipe which is introduced in the hole 2 and preferably rests on the bottom thereof and is preferably provided with a number of air holes 3^a about the bottom so as to permit the escape of air around the sides if, for any reason, the end should become clogged up.

4 indicates a coupling for the connection of an air pipe and the air valve is indicated

at 5. A glass covered peep-hole 6 is provided in the ends of the coupling 4 opposite the pipe 3 so as to permit observation of the interior of the air pipe through the 5 peep-hole if desired. The kindling, as pieces of oil-soaked wood, which is placed in the hole, is indicated at 7, and the fuel for supporting continued combustion, as coke, coal, charcoal or the like, is indicated 10 at 8. Other combustible material as, for example, gas or oils or other liquid combustibles, may be used in place of the solid combustibles, as will be understood, and in such case may be introduced by means of a suitable 15 pipe which, however, is not illustrated and, as already stated, if additional moisture is required, a steam or water pipe may be provided for that purpose which, however, as in the case of the pipe for liquid combustibles, has not been illustrated. The irregular 20 line 9 indicates the cross-sectional outline of burned or calcined part of the rock extending about the original position of the drilled hole 2, the size of such calcined portion and of the 25 resulting pocket formed when the calcined material is hydrated and removed being, within reasonable limits, under the control of the operator, who may vary the quantity of fuel, the amount of air supplied and the 30 time during which the combustion is carried on to suit the circumstances of the individual case.

As already stated, when the combustion has been completed and sufficient material 35 calcined, the calcined material may be hydrated and cleaned out with water, and the final cleaning out may be completed as by means of a sludge pump, leaving the enlarged opening ready to receive its charge 40 of explosive.

When a wet hole is encountered, the water entering through crevices or cracks in the rock, it is only necessary to fill the hole in the neighborhood of the cavity with cement 45 or plaster, and after the crevices are sealed up thereby the cement or plaster can readily be drilled through, or a suitable core may be inserted and the cement or plaster introduced around it, the core, as a piece of pipe, 50 being revolved while the plaster or cement is setting, and removed as soon as the plastic material has sufficiently set, either mode of treatment leaving the crack or crevice sealed up and preventing the ingress 55 of water, and leaving a substantially dry hole for the burning process. If the cement or plaster is used to stop a crevice in the region where the calcining takes place it becomes loose and is broken out upon the 60 swelling produced by the hydration of the calcined rock and can be removed with the other material of the cavity. Such sealing may be carried on much more conveniently and effectively with a small drilled hole

such as may be used with the present process 65 than would be the case if drilled holes were made of sufficient diameter to accommodate therein, without enlarging, the large quantities of explosives needed.

This improved process effects numerous 70 important economies; a saving is made in the cost of drilling, the explosive has increased effectiveness, being arranged compactly in a chamber where its effect is concentrated, and a saving in explosives is 75 thereby effected, and the spacing apart of drilled holes may be increased, and generally effective blasting operations can be carried on with greater economy, certainty and precision. 80

While I have described and illustrated certain apparatus for carrying out my improved process, it is to be understood that the same is illustrated and described only for the purpose of making my invention 85 clear, and that my invention is not in any manner limited thereby.

Having thus described my invention, I claim:

1. The process of opening a hole in calcinable rock, applying heat within said hole for calcining the rock, hydrating the calcined material, and removing the calcined hydrated material leaving an enlarged opening therein, substantially as set forth. 90 95

2. The process of forming a small diameter hole in calcinable rock, applying heat within said hole to the rock to calcine the same, hydrating the calcined material, and flushing it out with water, substantially as 100 set forth.

3. The process which consists in mechanically opening a small diameter hole in calcinable rock, burning solid fuel and supplying air to support combustion therein, 105 hydrating the calcined material, and flushing it out together with the solid products of combustion with water, thereby forming an enlargement or pocket in the region where combustion takes place, substantially as set 110 forth.

4. The process which consists in mechanically forming an opening in calcinable rock, supplying air and combustibles within said opening, and igniting such combustibles and supplying additional combustible material to support combustion therein, and hydrating and removing the calcined material, thereby forming an enlargement of said opening sufficient to accommodate large 120 quantities of explosives, substantially as set forth. 115

5. The process which consists in drilling a hole in calcinable rock, supplying air and combustibles within said opening, and igniting such combustibles and supplying additional combustible material to support combustion therein, and hydrating and wash- 125

ing out the calcined material, and finally
cleaning out the hole with a sand pump,
thereby forming an enlargement of said
opening sufficient to accommodate large
quantities of explosives, substantially as set
forth.

In testimony that I claim the foregoing, I

hereunto set my hand, this 8th day of Jan-
uary, 1915.

WILLIAM H. MASON.
